HIGH-FREQUENCY RADIO AMPLIFYING
CIRCUITSWladimir J. Polydoroff, Wilmette, Ill., assignor
to Johnson Laboratories, Inc., Chicago, Ill., a
corporation of Illinois

Application February 11, 1936, Serial No. 63,298

6 Claims. (Cl. 179—171)

The invention relates to radio receiving apparatus and more particularly to permeability-tuned circuits for use in the high-frequency range between approximately 5 and 20 megacycles. The circuit losses at these high frequencies are of much greater magnitude than at the lower radio frequencies and additional losses which are unnoticeable at frequencies below about 5 megacycles become predominant. For example, the input conductance of the usual type of high-frequency thermionic amplifier tube increases as the second power of the frequency, and becomes a factor of real importance at the higher radio frequencies. One object of the invention is the material reduction of the effect of these losses upon the selective properties of the variably tuned circuits employed in a radio receiver. Another object of the invention is to provide a novel circuit arrangement which is characterized by substantially uniform gain and selectivity throughout this frequency range.

A high-frequency variable inductance device for employment at these high frequencies preferably has a core of substantially the same length as the winding. The circuit arrangement of my present invention, which employs these variable inductance devices to secure an increased efficiency at the higher radio frequencies, will be better understood if the following description is taken in connection with the accompanying drawing, in which:

Fig. 1 is a schematic diagram of a circuit embodying the invention, and

Fig. 2 is a graph showing a comparison of the operating characteristics of my improved circuit as exemplified by the embodiment of Fig. 1 as against those of conventional circuit arrangements.

Fig. 1 shows a circuit suitable for the reception of high-frequency signals. Antenna circuit 1 is inductively coupled by means of a small primary winding 2 to a selective circuit 3 consisting of winding 4, the inductance of which is adjusted by movement of ferromagnetic core 5, and capacitor 6. When circuit 3 is tuned to resonance with an incoming signal, a maximum voltage will be developed across winding 4 representing a magnification of the signal voltage of approximately three times. The voltage thus obtained is normally applied directly to the grid 1a of a thermionic tube 7.

At a frequency at the upper end of the tuning range, for example, 20 megacycles, the ferromagnetic core 5 is completely withdrawn from the winding 4 and the characteristics of circuit 3 by

itself are determined by the properties of winding 4, capacitor 6 and the losses which are reflected through the primary winding 2 from the antenna. This circuit as such may readily be designed to produce satisfactory selective properties. However, if the high-potential terminal of this circuit is connected directly to the grid 1a of thermionic tube 7, new losses are introduced, due to the electronic loading effects of the thermionic tube at high frequencies. As pointed out by Ferris in the Proceedings of the Institute of Radio Engineers for January 1936, at pages 82—107, the input conductance of vacuum tubes increases as the square of the frequency, and thus seriously affects the performance obtainable even at moderately high radio frequencies. Thus, while the circuit itself has desirable characteristics, as indicated by its L/R ratio or its "Q", the connection of the circuit to the thermionic tube causes a reduction of both gain and selectivity to approximately one-half of their original values. The arrangements of the present invention substantially overcome this disadvantage and provide a high degree of efficiency at the higher radio frequencies. In the lower frequency region, however, corresponding to the position of the core inserted all the way into the winding 4, the losses due to the electronic load of the thermionic tube are greatly diminished and the circuit operates substantially at its normal efficiency.

In accordance with the invention, and as shown in Fig. 1, the grid 1a of tube 7 is connected to a tap 8 on the winding 4. Thus only a portion of the voltage developed across the circuit 3 is applied to the grid of the tube. This arrangement greatly reduces the damping effect of the tube upon resonant circuit 3, since its input conductance is impressed across only a portion of winding 4, and therefore this arrangement provides greater selectivity than would be realized were the grid 1a to be connected directly to the high-potential terminal of the winding 4. Additionally, since the inductance gradient of the winding 4 is redistributed by the relative movement of the core 5, the electrical location of the tap 8 is also varied. If the winding is uniform and its field is not materially affected by the position of the winding 2, the tap 8 may be advantageously located at the electrical center of the winding. Under these circumstances, when the core is completely withdrawn from the winding, so that it has substantially no effect upon the coil, the tap will also be at the center of inductance of the winding. However, as soon as the core starts to enter the coil, the inductance of the

lower portion of winding 4 is increased by the presence of the core, so that the grid circuit of tube 7 includes more than one-half of the total inductance. This is because the core enters that 5 end of the winding which is connected to the ground. As the core is advanced further into the winding, the electrical position of the tap is shifted still further towards the high-potential end of the winding, and the value of the portion 10 of the inductance in the grid circuit of tube 7 is still further increased. At the same time, the selectivity tends to be decreased due to the increased damping effect of tube 7 on the circuit 3.

When the core 5 is about midway of its travel, 15 the shift of the electrical position of the tap 8 is at its maximum. As the core advances past this position and still further into the winding, the shift of the electrical position of the tap gradually diminishes, until at the end of the travel, when the core is all the way in, the electrical position of the tap again corresponds approximately to the original position, and the tap is effectively at the center of inductance of the winding. Under this condition, the damping effect 20 of the input conductance of tube 7 on the selectivity of circuit 3 is a minimum, as explained above with reference to the high-frequency position of core 5.

It will be understood that by placing the tap 30 at some point other than at the electrical center of the winding, the maximum shift in its electrical position, as the core advances into the winding, may be changed. Thus by proper choice of the original location of the tap, the degree of shift may be varied to suit particular 35 conditions, and to overcome or reduce undesired variations in the gain and selectivity of the system as it is tuned over a range of frequencies.

In Fig. 2, curve A indicates the gain between 40 the antenna circuit 1 and the grid 7a of tube 7 in the circuit of Fig. 1, but with grid 7a connected to the high-potential terminal of winding 4. Due to the electronic load of the tube 7, the amplification is considerably poorer at the 45 upper frequencies than at the lower frequencies, resulting in non-uniform and inefficient performance. The gain due to the voltage developed across the coil 4 depends on the electrical position of the tap 8. At the high-frequency end with the core withdrawn, the gain is reduced; then, as the core moves in, the gain is increased and at the lowest frequency, when the core is fully in, is reduced again. On the other hand, the gain also depends on the damping effect 50 due to the input conductance of the tube 7. At the high-frequency end of the tuning range the damping is greatest, but the load reflected in the circuit 3 is minimized because of the action of the tap 8. The reduction of voltage gain is thus compensated by the reduction of damping. At the lowest frequency, when damping due to 55 the tube is negligible, an abnormal increase in gain would occur, as shown in curve A; but this increase in gain is compensated for by the action of the tap 8, thus producing substantially uniform gain throughout the entire frequency range. Curve B indicates the gain which is realized with the improved arrangement shown in Fig. 1.

Although the amplification at the higher 60 frequencies remains substantially the same as before, in spite of the reduction in the voltage applied to the grid 7a of the tube 7, because of the diminished load on tuned circuit 3, the selective properties, indicated in Fig. 2 as "selectance", i. e., the band width in kilocycles at half 65

amplitude, are materially improved as clearly explained in preceding paragraphs. This is indicated by a comparison of curve C, which shows the selectance of the circuit of Fig. 1, with curve D, which shows the selectance obtained when 5 the grid 7a of tube 7 is connected to the high-potential terminal of winding 4.

When tuning is accomplished by movement of a homogeneous ferromagnetic core, a decrease 10 in the amplification beyond that to be expected due to the change in frequency normally occurs in the middle region of the tuning range. If the frequency range to be covered is the standard broadcast band from 540 to 1600 kilocycles, this 15 non-uniformity of amplification is readily overcome by utilizing a core having varying magnetic density, as described in my United States Patent No. 1,982,689. This expedient, however, is difficult to apply at the higher radio frequencies, since the permeability of the cores for use at 20 these frequencies is already considerably reduced by the necessary finer subdivision of the iron and relatively thicker film of insulation between adjacent particles.

For these higher radio frequencies, my present 25 invention provides a simple and advantageous arrangement for securing substantially uniform amplification and substantially constant selectance with a homogeneous core. At an intermediate position of the core 5, corresponding to a 30 frequency near the center of the range, the redistribution of the inductance gradient of the winding 4 causes the tap 8 to electrically shift toward the high-potential terminal of winding 4. Thus a higher voltage is applied to grid 7a 35 and the amplification of the circuit is increased at the middle frequencies. When the core is all the way in the winding 4, however, the tap 8 is electrically shifted back to its original position near the electrical center of the winding 4, 40 and the amplification is, therefore, about one-half what it would be were the grid 7a of tube 7 to be connected to the high-potential terminal of winding 4. With this arrangement, not only is the gain substantially uniform throughout the 45 tuning range of the system but also the selective properties are greatly improved, as indicated by curve C, due to the reduction in loading of the tuned circuit 3 by the tube 7.

The thermionic tube 7 may be connected to 50 a second tuned circuit 9, and a tap 10 on the winding 11 may be employed to apply a voltage to the grid of a second thermionic tube 12. The second circuit will have substantially the same 55 improved performance over a range of frequencies as does the first circuit, and the cores 5 and 13 may be ganged for simultaneous movement, to simultaneously and synchronously tune the two circuits. It will be understood that tube 7 or tube 12 may function otherwise than as an 60 amplifier without departing from the scope of the invention.

The circuit of Fig. 1 may be employed in the preselector system of a superheterodyne radio receiver, or any desired number of stages of the 65 type shown may be operated in cascade in a receiver of the tuned radio-frequency type. In either case, by properly locating the tapped grid connection on the windings, the receiver may be designed to have substantially uniform amplification and considerably more nearly constant selectivity over a range of high radio frequencies.

Having thus described my invention, what I claim is:

1. A high-frequency system including a reso- 75

- nant circuit and a vacuum tube having a grid, said resonant circuit including a fixed capacitor and a variable inductor having a winding and a high-frequency ferromagnetic core movable relatively thereto to vary the inductance of said winding and thereby tune said circuit over a range of frequencies, and means whereby a variable portion of the resonant voltage developed across said winding is applied to said grid, said portion depending upon the position of said core relative to said winding.
2. A high-frequency system including a resonant circuit and a vacuum tube having a grid, said resonant circuit including a fixed capacitor and a variable inductor having a winding and a high-frequency ferromagnetic core movable relatively thereto to vary the inductance of said winding and thereby tune said circuit over a range of frequencies, and a connection from said grid to a point on said winding whereby the portion of the resonant voltage developed across said winding which is applied to said grid varies as said circuit is tuned over said range of frequencies.
- 25 3. A high-frequency system including a resonant circuit and a vacuum tube having a grid, said resonant circuit including a fixed capacitor and a variable inductor having a winding and a high-frequency ferromagnetic core movable relatively thereto to vary the inductance of said winding and thereby tune said circuit over a range of frequencies, and means including a connection from said grid to a point on said winding whereby a variable portion of the resonant voltage developed across said winding is applied to said grid, said portion depending upon the position of said core relative to said winding.
- 35 4. A high-frequency system including an input circuit, a resonant circuit inductively coupled to said input circuit, and a vacuum tube having a grid, said resonant circuit including a fixed capacitor and a variable inductor having a winding, a tap on said winding and a connection from said tap to said grid, and a high-frequency ferromagnetic core movable relatively to said winding for simultaneously tuning said circuit over a range of frequencies and altering the electrical position of said tap to secure substantially uniform gain throughout said range.
5. A high-frequency system including an input circuit, a resonant circuit inductively coupled to said input circuit, and a vacuum tube having a grid, said resonant circuit including a fixed capacitor and a variable inductor having a winding, a tap on said winding and a connection from said tap to said grid, and a high-frequency ferromagnetic core movable relatively to said winding for simultaneously tuning said circuit over a range of frequencies and altering the electrical position of said tap to secure substantially constant selectance throughout said range.
6. A system for operation in a range of high frequencies including a resonant circuit and a vacuum tube having a grid and high grid-circuit losses in said range, said resonant circuit including a fixed capacitor and a variable inductor having a winding, a tap on said winding and a connection from said tap to said grid to materially decrease the effect of said losses upon said resonant circuit, and a high-frequency ferromagnetic core movable relatively to said winding for simultaneously tuning said circuit over said range and altering the electrical position of said tap to secure substantially uniform gain and substantially constant selectance throughout said range.
